UNITED STATES PATENT OFFICE.

OSBORN P. LOOMIS, OF SOMERVILLE, MASSACHUSETTS, ASSIGNOR TO THE LOOMIS ELECTRIC MANUFACTURING COMPANY, OF NEW YORK.

COMMUTATOR-BRUSH AND HOLDER.

SPECIFICATION forming part of Letters Patent No. 407,225, dated July 16, 1889.

Application filed February 23, 1889. Serial No. 300,898. (No model.)

To all whom it may concern:

Be it known that I, OSBORN P. LOOMIS, a citizen of the United States, residing at Somerville, in the county of Middlesex and State of Massachusetts, have invented certain new and useful Improvements in Commutator-Brushes and Holders Therefor, of which the following is such a full, clear, and exact description as will enable any one skilled in the art to which it appertains to make and use the same, reference being had to the accompanying drawings.

My invention relates to commutator appliances for dynamo-electric machines, and is equally applicable to such machines whether generators or motors.

The principal objects of the invention are to so improve the commutator-brush, the brush-holder, and its mountings and immediate connections that the strips or laminæ of the brush may possess greater elasticity and yet be stout enough to resist bending or buckling up; that the brush may bear upon the commutator-cylinder with a yielding spring-pressure, so as to be held in close engagement therewith; that the machine may be reversed without necessitating readjustment of the brushes, and that good electric connection or circuit between the commutator and the terminals may be obtained.

To these purposes the invention consists in the certain novel and peculiar constructions and arrangements of the brush, the brush-holder, and its mountings and connections, all as hereinafter fully described, and then pointed out in the claims.

In the accompanying drawings illustrating my invention, and in which like numbers of reference designate like and corresponding parts throughout, Figure 1 is a reduced view of my improved apparatus, taken in section on line 1 1, Fig. 2. Fig. 2 is a plan view of the apparatus with part of the armature shown. Fig. 3 is a detached detailed view, partly in section.

Referring to the drawings, the number 5 designates the armature, 6 the armature-shaft, and 7 the commutator-cylinder mounted on and turning with the said shaft and hav-

ing the usual radial commutator-segments. 50 Upon the shaft 6, and toward the outer end thereof, is the brush-holder yoke 8, provided with the insulated handle 9, and so mounted on the armature-shaft as to be rotatable thereon in a vertical plane, in the usual way, 55 in order to shift the position of the brushes relative to the commutator.

At or near each end of the yoke 8 is secured a metallic terminal-plate 10, which is fastened in position by means of screws 11 11, set in 60 the yoke, and the plate is completely insulated from the yoke by suitable insulating material 12—vulcanite, for instance. The plate has a binding-post 13, which serves as a terminal for the machine. The plate is provided with 65 two perforated hinge-ears 14 14, preferably cast therewith, and into the perforations of which take the pintles 15 15 of the swinging brush-holder 16, which is arranged so as to swing in a plane parallel with or containing 70 the axis of the commutator cylinder or shaft, and it is movable in toward or out from the commutator in a manner that is evident from the drawings.

To the inner face of the brush-holder is attached by suitable screws 17 the back or bed plate 18 of the commutator-brush, which is composed of flat strips 19 19, made of suitable metal. These strips or laminæ are preferably soldered to the bed-plate 18, though 80 they may be attached thereto in any other suitable way.

The shape of the brush-laminæ 19 is peculiar and constitutes part of my invention. In shape the leaves or laminæ 19 are flat, with a 85 broad base 20, from where they taper to their free contact ends 21, which are formed on arcs about of a curvature equal that of the commutator, with which they are held in sliding contact. The contact ends are also beveled 90 off, as clearly indicated in Fig. 2, so that the contact-making surfaces thereof are considerably increased. By virtue of this peculiar shape the laminæ are rendered very pliant. At the same time they are sufficiently rigid 95 and stout near their attaching ends or bases to resist any stress that would tend to make them bend or buckle up transversely.

The brush-laminae bear obliquely end-on upon the commutator, and are each disposed in a plane that is oblique to the axis of the commutator 7 and normal to the plane of the 5 commutator-segment passing thereunder.

Electrical connection between the terminal-plate 10 and the brush-holder 16 is made by means of the hinge ears and pintles, and also by means of the contact-spring 22, secured to 10 the plate by screws 23 and bearing upon the rounded end 24 of the brush-holder. This contact-spring is split at its free end into fingers in order to insure more perfect contact. The brush-holder 16, and thus the brush carried thereby, is forced in toward the commutator 7, under yielding spring-pressure, by the coil-spring 25, connected by one end to the holder and by the other end to the brush-holder yoke 8, which, considered in reference 15 to the plane in which the holder swings, is fixed. The tendency of spring 25 is to normally hold the brush-holder in toward the commutator, and this causes the brush to bear thereon with a yielding pressure, in addition 20 to the spring-pressure imparted by the brush-laminae themselves.

To have a circuit lead over a hinge-joint or sliding contacts is objectionable for several obvious reasons. In the case of a hinge-joint 30 the same necessarily has to be lubricated, and the caking of the lubricant is a great disadvantage. In my improved apparatus I am enabled to easily avoid this by placing the terminal 13 directly upon the brush-holder 16, 35 as indicated in broken lines in Fig. 2. If preferred, the pindle 15 of the holder may be extended and fashioned into a suitable binding-post. In both of these latter constructions making circuit over sliding contacting-surfaces is obviously avoided.

The several parts of the described apparatus are to be made of suitable metals where electrical conduction is required. The parts are duplicated upon diametrically-opposite 45 sides of the commutator and the yoke in a way that will be readily understood from the drawings.

From the oblique arrangement of the brush-laminae and the pressure of the brush-holder 50 in toward the commutator the laminae are always maintained in close broadside contact with each other and kept well bunched. Should a strip 19 become hooked in a commutator-segment it would be easily stripped 55 from the brush without likely damage to the adjacent laminae.

The improved apparatus provides a very flexible brush, giving good electrical connections, and one that does not require shifting 60 upon reversal of the machine.

I do not confine myself to the exact constructions and arrangements herein shown, for obviously there may be various modifications made in the same without, however, making 65 a substantial departure from the spirit of the invention.

The springs 25 are of course to be insulated in a suitable manner, so as not to connect the holder and yoke electrically. I have shown an insulated socket in the yoke, in which is 70 set the hook for securing the spring to the yoke. These sockets are indicated in solid black. If preferred, a hard-rubber hook can be used.

Having thus described my improvements, 75 what I claim as my invention, and desire to secure by Letters Patent, is—

1. In a dynamo-electric machine, the combination, with the commutator-cylinder, of a terminal-plate mounted on a support and insulated therefrom, and a brush-holder having a brush and hinged to said plate, for the purpose set forth. 80

2. In a dynamo-electric machine, the combination, with the commutator-cylinder, of the brush-holder yoke and a terminal-plate 85 mounted thereon and insulated therefrom, a brush-holder carrying a brush and hinged to said plate, and a spring for forcing the holder in toward the commutator to hold the brush in 90 engagement therewith, substantially as and for the purpose set forth.

3. In a dynamo-electric machine, the combination, with the commutator-cylinder, of a brush composed of the strips or laminae 19, 95 19, 20 and tapering toward their attaching ends 20 and 100 tapering toward their contact ends 21, whereby the laminae may be pliant, at the same time stout enough to resist buckling up, substantially as set forth.

4. In a dynamo-electric machine, the combination, with the commutator-cylinder 7, of the brush-holder yoke 8, the terminal-plate 10, mounted thereon and insulated therefrom, the swinging brush-holder 16, carrying a brush 105 and hinged to the said plate in electrical connection therewith, the spring 22, mounted on the said plate 10 and engaging the said brush-holder 16, the terminal-post 13, and a spring for forcing the holder in toward the 110 said commutator, substantially as and for the purpose set forth.

5. In a dynamo-electric machine, the combination, with the commutator-cylinder 7, of the brush-holder yoke 8, the terminal-plate 10, mounted on and insulated from the yoke, the swinging brush-holder 16, carrying a brush 115 and hinged to said plate 10, in electrical connection therewith, the spring 22, mounted on the plate 10 and engaging the holder 120 16, the terminal-post 13 and the spring 25, intermediate the holder 16, and yoke 8, for forcing the holder in toward the commutator, substantially as and for the purpose set forth. 125

6. In a dynamo-electric machine, the combination, with a swinging brush-holder, consisting in a bar, such as a bar 16, of a bed-plate, such as a bed-plate 18, secured to the bar and having the brush-laminae attached 130 thereto, for the purpose described.

7. In a dynamo-electric machine, the com-

bination, with a terminal-plate 10, suitably mounted and insulated and provided with perforated hinge-ears 14, of a brush-holder, such as 16, carrying a brush, and having 5 hinge-pintles 15, for hinging with the ears 14, substantially as and for the purpose set forth.

In testimony whereof I have set my hand

and affixed my seal, this 20th day of February, 1889, in the presence of two subscribing 10 witnesses.
